MANUFACTURE OF HATS

Walter Wolf Winsen, Johannesburg, Transvaal,
Union of South AfricaApplication November 14, 1941, Serial No. 419,091
In the Union of South Africa August 23, 1941

1 Claim. (Cl. 2-192)

This invention relates to the manufacture of hats, more particularly to the production of the brims of hats from flat material such as woven straw.

Various ways have been proposed for producing hat brims of this type. One proposal provided a block or form on which the damped material was stretched and fastened so that on drying it was shaped as desired. Preferably there were two thicknesses of the material in the brim and to reinforce it there was formed at the edge an inwardly directed fold so as to make at this point four thicknesses of material. At the same time an upright portion of the same material around the centre opening in the brim was provided as a means of attaching the crown of the hat.

This invention is for an improved hat brim of this type, in which the finished brim has a single smooth reinforced edge. The entire brim is formed in one operation and from one piece of material using for its production a block or form of special design. The finished article has an enhanced artistic effect in that the weave of the material, such as straw, is so set during the forming operation that the straws become curved giving, what is known in the art, an exotic effect, and with the double thickness of straw a moiré is formed.

The invention is illustrated in the accompanying drawing in which

Fig. I is a side elevation, partly in section, of a block specially designed for forming the hat brim herein described.

Fig. II is a section of the hat brim as formed on the block shown in Fig. I.

Fig. III is a similar view showing how the material is pressed to form the finished brim.

Figs. IV and V show modifications.

Figs. VI and VII show the details in the construction of the blocks.

Fig. VIII shows the material ready for the block.

Fig. IX shows a finished brim.

Fig. X is a sectional view of a modified form of block and

Figs. XI, XII and XIII are sections of modified forms of brims.

In the drawing 10 is the material which is usually a strip cut diagonally or on a bias from a flat woven sheet with its short edges 11-11 stitched together so that it becomes a cylinder 12 of the required size. In some cases the cylinder of material may be made without a joint, for instance on a knitting machine, in the well known

manner. Said cylinder is made large enough to be pulled over the outside circumference of the forming block 13 and usually wide enough to form, the width of the brim twice over, one or more reinforcing folds, and also a turned up ring 14 for attaching the crown of the hat.

The block or form 13 may be made of any suitable material such as wood, plastics, or metal, for instance, aluminium, or a combination of such materials.

Thus in starting to form the brim, the cylinder 12 is turned inside out, that is with the finished or "right" side of the material on the inside of the cylinder. It may be damped to soften it and it is then passed over the block 13 so that the edge 15 is approximately half way down the height of the cylinder 12. A thin cord 16 is passed round the block 13 below the edge 15. This cord 16 is tightened either by expanding the space 20 between the two halves 17-17 of the block 13, as in Fig. VI, or by passing a loop 18 of the cord 16 through the material 10 (preferably at the seam 11) and through a small hole 19 in the side of the block and straining the cord by a spring, 25 lever, or other tensioning device 20.

The upper portion of the cylinder 12 of material 10 is now brought down over surface 21 and its edge 14 bunched up, whilst leaving the surface of the material on surface 21 smooth and secured by a cord 22 round the projection 23, see Fig. I, or down over edge 24, that is down inside the centre 25 of the block 13 and secured by pins or spring clips 26 or by other convenient means, see Fig. X. The lower portion of the cylinder 12 is now turned over the top portion of the material already in position on surface 21 of block 13 so as to make a fold over cord 16 and over the edge 15, that is the lower edge of cylinder 12, is brought over to meet the top edge 14 secured by cord 22 or by means 26 to form a double circle 14 of the material 10 upstanding from the surface of the double brim.

The material 10 is set by drying it in position on block 13. It is then removed by releasing the cord 16. Such release is effected by decreasing the circumference of the block 13 as shown in Fig. VI. For instance by screwing the nut 27 onto the screw 28 in the well known manner so that the two halves 17, 17, of block 13 are brought together; or, in an alternative construction, the cord 16 may be released by releasing the loop 18 from the tensioning device 20. Cord 16 is taken out from between the double thickness of material 10 as shown in section in Fig. II. It is then

stiffened, with a gum if necessary, and set by pressing in the well known manner, to form the section shown in Fig. III.

It will be seen from Figs. X, XI, XII and XIII that the reinforcing fold on the edge of the brim may be above or below the brim when the crown is fitted, depending whether the upper edges 14 of the material 10 are fastened with a cord 22 during formation of the brim on the block 13 or turned down over 24 and fastened in 25 as shown in Fig. X.

Fig. V shows the form of brim known prior to this invention. The edges 29, 30 were produced by a cord 16 fastened into a groove and exposed on the outside of the block so that it could be cut to remove it. The block in such a case was double ended so that each half of the cylinder 12 was formed on the top and bottom part of the block respectively. When pressed up the edges 29, 30 formed the reinforced edge for the brim but such edge when finished showed a double line and it was difficult to make the two edges 29, 30 perfectly coincide. Thus the edge was often unsightly. In contrast the edge 31, Fig. III, according to this invention, exposes only a single edge of material although the reinforcing of the edge of the brim is the same, namely four layers of material 10.

Should only one layer of material 10 be required for the brim, according to this invention, the cylinder 12 of material is narrower and its upper edge is brought below the edge 15 of the block but just far enough up for it to be fastened by cord 16 as above described. That is the upper half of the cylinder 12 is absent and only sufficient material is retained above the fold for cord 16 to hold the same. The lower portion of the cylinder 12 is then turned up over edge 15 and

finished as above described. The resulting section of the brim is shown in Fig. IV.

Should it be desired to have a second reinforced ring in the brim the block 13 is modified 5 to the form shown in section in Fig. X. The resulting sections of the brim are shown in Figs. XII or XIII. Figs. XII and XIII are alternative forms depending whether one or both layers of the material are caught in the recess 32 (Fig. X) 10 by a second cord 16. The form Fig. XIII will require two supplementary cords 16 or three cords in all as will be evident from the foregoing description of the operation and Fig. XIII.

In Fig. VIII is shown a portion of the weave 15 of the material making up the cylinder 12 and in Fig. IX is shown how the strands of the weave are curved by the manipulation of the material above described. It will be evident that because 20 the lower half of the cylinder of material is folded up over the top half, the angle of the bias in the weave will be reversed and consequently the subsequent curves will lie in the reverse direction. The superimposition of the material and consequently 25 the semi-superimposition of these curves in the top and bottom layers of material 10 will give to the finished brim a beautiful moiré effect when a woven material such as straw is used.

What I claim as new and desire to secure by Letters Patent is:

30 A hat brim made of a single piece of woven fabric and consisting of two thicknesses of the material having the strands making up the weave radiating in curves and in opposite directions in each thickness and reinforced at the edge by a fold upon itself of the double thickness of the material.

WALTER WOLF WINSEN.
